ATTORNEY

UNITED STATES PATENT OFFICE.

CHARLES H. LEICESTER, OF OCEAN FALLS, BRITISH COLUMBIA, CANADA.

INTERLOCKING BRICK.

Application filed June 5, 1920. Serial No. 386,914.

To all whom it may concern:

Be it known that I, CHARLES H. LEICESTER, a citizen of Canada, residing at Ocean Falls, Province of British Columbia and Dominion of Canada, have invented certain new and useful Improvements in Interlocking Bricks, of which the following is a specification.

The present invention relates to improvements in building blocks or bricks and aims to provide a novel and improved building block or brick preferably for constructing walls, furnaces and other structures.

It is the object of the invention to provide building blocks or bricks of the nature indicated, which may be simply and inexpensively molded or otherwise fashioned and which will interlock so as to present a wall or structure which cannot split open in any direction across that for instance in which the bond is laid.

Another object of the invention is to provide building blocks or bricks especially adapted for building furnaces whereby a strong, durable, efficient and inexpensive structure is created preventing the collapse of the furnace walls.

With these and other objects in view, which will appear as the description proceeds, the invention resides in the construction and arrangement of parts and in the details of construction hereinafter described and claimed, it being understood that changes may be made in the size and proportion of the several parts and minor details of construction without departing from the spirit of the invention or sacrificing any of the advantages of the invention.

The invention is shown on its preferred embodiment in the accompanying drawing, wherein—

Figure 1 is a perspective view of the improved building block or brick.

Figure 2 is a top plan view of a wall constructed of building blocks made according to the present invention, with bond laid across the wall.

Figure 3 is an end elevation of a wall constructed of bricks according to the present invention, and

Figure 4 is an elevation of a wall constructed of building blocks made according to the present invention, with bond laid longitudinally.

The present building block comprises a body 10 provided with a key portion 11 projecting from one of its faces intermediate the ends of the body 10. Upon its opposite face the body 10 is provided with a pair of key portions 12, 12' projecting from its face with the ends of the body 10.

As shown in Figure 2, a wall is constructed by superposing a plurality of layers 13 of bricks with the bond laid across the wall. Each of said layers being constructed of a plurality of juxtaposed stones 10, so arranged, that half of the key portion 11 on one stone is directed towards the right of said figure, fits into the space 14 formed by half the key portions of two adjoining stones 10 of the next row, while the space 15 between the two key portions 12 and 12' of the stone 10 is directed towards the left in Figure 2 and is engaged by the portions 12 and 12' of the stone or brick of the next succeeding row.

Figure 3 shows the end faces 16 of the stones and Figure 4 shows an elevation view of a wall constructed of stones 10 with bond laid longitudinally, the upper and lower row shown without any keys 11 so that openings 17 are formed between the upper and lower rows and the rows adjoining said upper and lower rows respectively.

From the foregoing, taken in connection with the drawing, the advantages and capabilities of the present invention will be obvious to those versed in the arts without further comment.

Having thus described my invention what I claim as new and desire to protect by Letters Patent of the United States is as follows—

In a wall construction of the character described with the bond laid longitudinally, a plurality of layers of juxtaposed blocks, key portions on said blocks forming spaces, the key portions of the blocks in one row of blocks fitting into the spaces formed by the key portions on the opposite side of the blocks in the adjoining row, and keyless blocks to form the upper and lower rows for forming openings between said upper and lower rows and the rows next adjoining said upper and lower rows.

In testimony whereof I have affixed my signature.

CHARLES H. LEICESTER.
